UNITED STATES PATENT OFFICE.

WALTER V. KAMP, OF NEW YORK, N. Y.

AIRSHIP.

1,108,113.

Specification of Letters Patent. Patented Aug. 18, 1914.

Application filed April 7, 1914. Serial No. 830,264.

To all whom it may concern:

Be it known that I, WALTER V. KAMP, a citizen of the United States, residing at New York, in the county of New York and State of New York, have invented new and useful Improvements in Airships, of which the following is a specification.

This invention relates to air ships and it consists in the novel features hereinafter described and claimed.

An object of the invention is to provide in an air ship a main body of special structure having within the same a series of compartments or gas bags each said bag being provided with a valved nipple. Passageways are provided between the side walls of the gas bags and the side wall of the body and means is provided for forcing or circulating air through the said passageways

whereby the surfaces of the gas bags may be maintained at a desired temperature.

Another object of the invention is to provide in combination with a body as above indicated a boat shaped car suspended from the body and in which is located suitable engines or motors. A propeller is located at the forward end of the body and is adapted to be operated by one of the engines or motors for forcing the air back through the passageways in the said body.

Another object of the invention is to provide in combination with a body and car as above indicated laterally disposed planes having propellers journaled at the rear portions thereof. One of the engines carried by the car is adapted to operate the last mentioned propellers.

Another object of the invention is to provide in combination with the body as above indicated means for receiving wireless telegraph messages.

In the accompanying drawings:—Figure 1 is a side elevation of the air ship. Fig. 2 is a front elevation of the same. Fig. 3 is a plan view of the forward portion of the body of the air ship with parts in section and parts broken away. Fig. 4 is a transverse sectional view of the body of the air-ship. Fig. 5 is a detailed sectional view of a portion of the body. Fig. 6 is a perspective view of one of the gas bags used in the body.

The air ship includes a body 1 which is of the usual cigar or elliptical external configuration. The body 1 is provided at its rear end with a suitable rudder 2 and at its forward end with a propeller 3 which is

mounted upon a shaft 4 indicated by dotted lines in Fig. 1 of the drawings.

A boat-shaped car is suspended from the body 1 and may if desired be provided with wheels 6 and a standard 7. Engines 8 and 9 indicated by dotted lines in Fig. 1 are mounted in the boat-shaped car 5 and a chain 10 operatively connects the shaft of the engine 8 with the shaft 4 of the propeller 3. Laterally disposed planes 11 are mounted at the opposite sides of the forward portion of the body 1 and propellers 12 are journaled for rotation at the rear portions of the said planes 11 and at points between the ends thereof. Chains 13 operatively connect the shaft of the engine 9 with the shafts of the propellers 12. A wireless telegraph receiver 14 is mounted upon the top of the body 1.

Gas bags or receptacles 15 are located in the intermediate portion of the body 1 and the said bags are preferably cylindrical in shape as indicated in Fig. 6 of the drawing. Each bag is provided with valved nipple 16 which passes through the side of the body 1 as best shown in Fig. 4 of the drawing.

The bags 15 are surrounded by spirally wound strips 17 and the said strips are relatively thick. Other strips 18 are also spirally wound around the gas bags 15 and are arranged one upon another as best indicated in Fig. 5. The strips 18 cross the strips 17, that is to say the said strips 18 are spirally wound about the bags 15 in the opposite direction from that in which the strips 17 are wound. The strips 18 in approximately parallel lines are spaced from each other and the strips 17 are spaced from each other thereby providing passageways between the body 1 and the surfaces of the gas bags 15. The body 1 is provided at its forward end with an opening 19 which is centrally positioned with relation to the propeller 3 and which is spaced from the shaft 4 which carries the said propeller 3.

From the above description taken in conjunction with the accompanying drawing it will be seen that when it is desired to permit the gas to escape from any one of the gas bags 15 the nipple 16 may be manipulated to permit such escapement of gas.

When it is desired to circulate air about the peripheries of the gas bags 15 for the purpose of maintaining the bags at a desired temperature the propeller 3 is rotated by the engine 8 and consequently a blast of air is

forced in a rearward direction through the opening 19 at the forward end of the body 1 and this air passes rearwardly through the passageways between the strips 17 and 18 5 and consequently the gas bags and their contents may be maintained at a temperature substantially the same as that of the external atmosphere. By such an arrangement the pressure of the gas confined within the 10 gas bags is maintained approximately at a uniform degree with relation to the pressure of the external atmosphere.

Having described the invention what is claimed is:—

- 15 1. In an air ship a body, gas bags located in the body, strips wound around the gas bags and spaced from each other and spacing the bags from the body and means for forcing air through the space between the 20 gas bags and the body.
2. In an air ship a body, gas bags located therein, strips spirally wound about the gas bags and spacing the bags from the body and means for forcing air through the space 25 between the gas bags and the body.
3. In an air ship a body, gas bags located in the body, strips spirally wound about the gas bags in one direction, other strips spirally wound about the gas bags in the opposite direction the strips of the two sets of 30 strips being spaced from each other and the said strips spacing the gas bags from the

body and means for forcing air through the space between the gas bags and the body.

4. In an air ship a body, gas bags located 35 in the body, strips spirally wound about the gas bags and spacing the bags from the body, said body having at its forward end an opening, a propeller mounted in front of said opening, means for rotating the propeller whereby the said propeller may force air through the said opening and through the space between the gas bags and the body. 40

5. In an air ship a body, gas bags located in the body, strips spirally wound about the 45 gas bags in one direction, strips spirally wound about the gas bags in an opposite direction, the members of the two sets of strips being spaced from each other whereby passageways are provided between the 50 gas bags and the body, said body having at its forward end an opening, a propeller journaled for rotation in advance of said opening, means for rotating the propeller whereby the said propeller forces air back through 55 the said opening and through the spaces between the gas bags and the body and through the spaces between the said strips.

In testimony whereof I affix my signature in presence of two witnesses.

WALTER V. KAMP.
